UNITED STATES PATENT OFFICE.

HENRY O. HAMILTON, OF CHICAGO, ILLINOIS, ASSIGNOR TO DANDY IRONING CRANE CO., OF CHICAGO, ILLINOIS, A CORPORATION OF ILLINOIS.

IRONING-MACHINE.

1,178,232.

Specification of Letters Patent.

Patented Apr. 4, 1916.

Application filed September 5, 1913, Serial No. 788,343. Renewed September 1, 1915. Serial No. 48,575.

To all whom it may concern:

Be it known that I, HENRY O. HAMILTON, a citizen of the United States of America, and a resident of Chicago, in the county of 5 Cook and State of Illinois, have invented certain new and useful Improvements in Ironing-Machines, of which the following is a specification.

This invention relates to that class of 10 ironing or pressing machines in which a heated smoothing-iron is supported by an overhanging track for movement by the operator in a horizontal plane over a table on which the garment to be pressed is 15 spread. And the present improvement has for its object to provide a simple, cheap and efficient structural formation and combination of parts whereby the dressing of a garment is attained in a ready and convenient 20 manner, and with which a convenient adjustment of the pressure or stress of the smoothing-iron upon the garment is provided, to suit the thickness, quality and 25 nature of the garment, all as will herein- after more fully appear.

In the accompanying drawings: Figure 1, 30 is a side elevation illustrating the general arrangement of parts in the preferred form of the present invention. Fig. 2, is a detail side elevation of the smoothing-iron carrier or support, with parts in section. Fig. 3, 35 is a detail end elevation partly sectioned of the lower portion of said carrier and the smoothing-iron. Fig. 4, is an enlarged detail section of the latch-mechanism of said carrier or support. Fig. 5, is a detail horizontal section on line α — α , Fig. 1, showing the side support or bracket for the smoothing-iron.

40 Similar reference numerals indicate like parts in the several views.

Referring to the drawings, 1 represents an overhead track, supported at its ends by any usual means above an ironing table 2, preferably by means of braced end posts 3, as shown in Fig. 1.

45 4 is a movable hanger or carriage having track wheels 5, by which it has movable engagement with the track 1. Said hanger or carriage is provided with a central tubular depending sleeve 6 forming the upper member of the hereinafter described carrier or support of the smoothing-iron.

50 7 is the intermediate member of said car-

rier or support, and preferably consists of 55 a round rod slidably disposed in the sleeve 6 aforesaid, and formed at its upper end with a bearing head 8, as shown.

9 is a coiled spring interposed between the bearing head 8 aforesaid, and the in-turned lower end of the sleeve 6, to provide 60 a yielding support between the parts, and so that in the ironing operation, a downward stress on the part of the operator will cause a corresponding downward movement 65 of the intermediate member 7 and the hereinafter described accessories which are carrier thereby.

10 is the main member of a latch mechanism, secured to the lower end of the intermediate member 7 aforesaid. In the construction shown, said latch member 10 is formed with vertically disposed guide orifices for the lower member of the support or carrier of the smoothing-iron, and with 75 a vertically disposed fulcrum flange or rib 11 for the rocking member of the latch mechanism.

12 is the vertically adjustable lower member of the carrier or support above referred to. Said lower member 12, preferably consists of a round rod slidably disposed in the aforesaid guide orifices of the latch member 10, and adapted to be locked at any required vertical adjustment by the 85 rocking member of the latch mechanism above referred to, and which in detail comprises a construction as follows: 13 is a rocking plate or member having a bearing or fulcrum on the flange 11 of the main 90 latch member 10, as shown more particularly in Fig. 4. At one end said rocking member is curved to form an operating thumb piece 14, while near its other end it is formed with an obliquely disposed orifice 15, which encompasses the lower member or rod 12, and normally has binding engagement with the sides of said member or rod 12 to hold the same to the required adjustment. 16 is a spring having 100 bearing on the upper surface of the rocking member 13, and adapted to yieldingly maintain said member in the above described locking engagement with the member or rod 12. 17 is a stud 105 bolt carried by the main latch member 10, and adapted to support and guide the spring 16 in its movements. 18 is a de-

19

pending angle bracket having an upper horizontal member 19 attached at its free end to the lower end of the lower member 12 of the smoothing-iron carrier aforesaid, 5 and a vertical member 20 which in turn is pivotally connected at its lower end to the carrying frame of the smoothing-iron now to be described. 24 is a laterally and horizontally disposed yoke or U shape frame, 10 attached by its respective end bars to the respective ends of the handle portion 22, of a smoothing iron 23, while its middle portion is pivotally connected to the lower end of the vertically disposed portion 20, 15 of the angle bracket 18, aforesaid, by pivot pin 25 passing through the aforesaid middle portion of the yoke 24, through the lower end of the brace bar 26, and through a hasp-shape bar 25 secured to said yoke, 20 as illustrated in Figs. 2 and 3. The lower end of the angle bracket 18 is disposed between the yoke 24 and the bar 25, and the construction is adapted to permit a limited rocking movement of the smoothing-iron 25 23 and its carrying frame, in a vertical plane.

With the described formation of the angle bracket 18 and carrying frame for the smoothing-iron, clearance around the handle of the smoothing iron is provided, 30 so that the operator can conveniently handle the same in actual use.

26 is a brace bar attached at its upper end to the vertical member 20 of the angle-bracket 18, aforesaid, and at its lower end is pivotally connected to the U shape carrying frame 24 of the smoothing-iron, 35 its function being to resist the sagging tendency of the smoothing-iron and carrying 40 frame due to the particular support of the parts above described.

In the present construction, the smoothing-iron 23 is supported above an ironing table 2, in a yielding manner which permits of its easy and convenient manipulation by the operator, and by means of the 45 described adjustment between the members or rods 7 and 12, any required degree of vertical adjustment of the smoothing-iron 50 can be attained to meet any and all ordinary requirements in the tailor trade. At the same time the described pivotal connections of the parts permit of a free horizontal movement of the smoothing-iron 55 in all directions over the table and the garment supported thereon.

27 is a bracket support secured in a horizontal plane to one of the end posts 3 aforesaid, and comprising a pair of forked bars 60 or tines, as shown in Fig. 5, between which the vertical member 20 of the angle bracket

18 is inserted, to support the smoothing-iron when not required for use.

Having thus fully described my said invention what I claim as new and desire to 65 secure by Letters Patent, is:

1. In an ironing machine, the combination of a horizontal overhead track, a carriage movable on said track, a depending member on said carriage, an intermediate vertical member yieldingly connected to said depending member, a lower vertical member connected to said intermediate member in a manner which permits extended vertical adjustment between the parts, a latch mechanism disposed at the point of connection between the intermediate and lower members and adapted to lock the lower member at the required vertical adjustment, 75 and a smoothing-iron pivotally connected to the lower end of said lower vertical member, substantially as set forth.

2. In an ironing machine, the combination of a horizontal overhead track, a carriage movable on said track, a depending member on said carriage, an intermediate vertical member yieldingly connected to said depending member, a latch mechanism carried at the lower end of said intermediate member and comprising a fixed latch member having guide orifices and a rocking member having an oblique binding orifice, 90 a lower vertical member disposed in the aforesaid orifices of the latch members, and a smoothing-iron pivotally connected to 95 the lower end of said lower member, substantially as set forth.

3. In an ironing machine, the combination of a horizontal overhead track, a carriage movable on said track, a depending member on said carriage, an intermediate vertical member yieldingly connected to said depending member, a latch mechanism carried at the lower end of said intermediate member and comprising a fixed 105 latch member having guide orifices and a rocking member having an oblique binding orifice, a lower vertical member disposed in the aforesaid orifices of the latch members, and a smoothing-iron pivotally connected to 110 the lower end of said lower member by a laterally disposed carrying frame affording clearance around the handle of the smoothing-iron, substantially as set forth.

Signed at Chicago, Illinois, this 4th day of September 1913.

HENRY O. HAMILTON.
